UNITED STATES PATENT OFFICE

FRANK A. BIEDERMAN, OF CHICAGO, ILLINOIS, ASSIGNOR TO PAPER PATENTS COMPANY, OF NEENAH, WISCONSIN, A CORPORATION OF WISCONSIN

CONTAINER

Application filed November 5, 1930. Serial No. 493,592.

My invention relates to fabrics which are particularly adapted for wrapping fragile articles, and in its preferred embodiment relates to a composite fabric formed of paper 5 or the like.

An object of my invention is to provide such a fabric which will comprise a soft mat adapted to contact with the fragile article to be wrapped, the said soft mat being backed 10 with a tough but flexible sheet, this backing sheet being sufficiently tough to resist tearing to a high degree and at the same time flexible enough to conform roughly to the shape of the wrapped article.

15 A further object is to provide such a composite fabric which will include between the soft mat and the flexible sheet a relatively stiff but expansible sheet, which serves to stiffen the composite fabric.

20 Still another object is to provide such a composite fabric which will be formed of inexpensive material, such as paper or the like.

Another object is to provide an improved 25 container, formed of the fabric above referred to, which is especially suitable for packing fragile articles.

Various other objects and advantages will appear as the description proceeds.

Referring now to the drawings forming 30 part of this specification:-

Fig. 1 is a plan view of a container representing a preferred embodiment of my invention, with parts of the layers broken away to show the composition thereof.

35 Fig. 2 is a sectional view taken on the line 2-2 of Figure 1.

Fig. 3 is an open end view of the container in open position, and

40 Fig. 4 is a perspective view of a composite fabric sheet embodying my invention.

According to the particular embodiment herein shown, 10 represents a mat or pad formed of a plurality of sheets of very thin crepe paper, any desired number of sheets 45 being used, in this case, five sheets. Obviously, any desired number of sheets may be used, of various grades and qualities of tissue or crepe paper. Adjacent and preferably secured to the mat 10, by glue or other suitable adhesive, is an interlining 12 of plain

smooth paper, which may be parchment paper, kraft paper, or the like. It will be noted that in the example shown, the pad 10 and stiffening sheet 12 are corrugated as a unit, the object of such unit corrugation being to 55 increase stiffness in one direction. Disposed outside the stiffening sheet 12 and in the present instance preferably secured thereto by a light coating of glue or other suitable adhesive is a sheet 13. This sheet is preferably 60 kraft paper which has been subjected to a creping operation. This paper is of relatively light weight but is extremely tough, i. e., resistant to tearing, and by reason of being crinkled may be stretched or elongated in a 65 direction transverse to the crinkles. It will be noted that the sheet 13 is applied so that the crinkles lie substantially parallel to the corrugations of the pad 10 and stiffening sheet 12.

The composite fabric above described may be used in any desired manner for packing fragile articles. The pad 10 is preferably disposed in immediate contact with the fragile article. The stiffening sheets aid in supporting the pad and protecting it from tearing and also are of value in absorbing shocks. Both the pad and the stiffening sheet, by reason of being corrugated, are expansible and also are of increased resiliency 80 as shock absorbers. The sheet 13 is also of great value in that it is extremely resistant to tearing and, is also extremely flexible adapting itself to any desired shape in the wrapping of an article and is expansible in 85 the same directions as the pad and stiffening sheets.

A preferred application of my invention is in the form of a container as shown in Figures 1 to 3. This container may be formed 90 by applying together two composite sheets of the type shown in Figure 4 in such manner that the pads 10 lie adjacent each other. The pads preferably dovetail, for economy of space in packing and to prevent crushing the corrugations. The two layers are cut into portions 15 of the desired size and shape. Preferably, the container 15 is rectangular in shape, a pair of staples 16 being applied adjacent one end thereof so as to form a closed 95

bottom for the container, the opposite end being unstapled in order that an opening may be formed between the similar portions of the container for the insertion of the article 18 which is to be packed. A staple 16' is also applied to each side of the container adjacent the open end, and another pair of staples 17 is applied and spaced further from the edges than the staples 16', also being spaced a short distance from the staples 16. In order to open the container for use, it being usually dispensed in its flat or unopened condition as shown in Figure 2, the edges adjacent the open end may be grasped with the fingers and the portions separated along the line represented by the meeting plane between the two mats 10, 10. A bag is thus formed, into which the article may be readily inserted.

Containers such as I have just described are found especially suitable for the packing of such fragile articles as vacuum tubes, electric light bulbs, and the like.

Various modifications of my invention will doubtless readily suggest themselves to those skilled in the art. Hence, I do not wish to be limited to the specific form shown, materials specified, or uses mentioned except as set forth in the appended claims, which are to be interpreted as broadly as the state of the art permits.

I claim as my invention:

1. As a new article of manufacture, a container comprising a pair of layers of relatively soft material disposed adjacent each other, and a pair of outside sheets of relatively tough but flexible material, and means securing said layers and sheets adjacent opposite edges thereof.

2. As a new article of manufacture, a container comprising a pair of mats of tissue paper or the like, said mats being corrugated as a unit, and a pair of outside sheets of relatively tough but flexible paper, and means securing said mats and sheets adjacent opposite edges thereof.

3. As a new article of manufacture, a container comprising a pair of relatively soft mats disposed adjacent each other, a pair of outside sheets formed of relatively tough but flexible material, and a pair of stiffening sheets interposed between said mats and said outside sheets, and means securing said mats and sheets adjacent opposite edges thereof.

4. As a new article of manufacture, a container comprising a pair of mats formed of tissue paper or the like, a pair of outside sheets formed of relatively tough but flexible material, and a pair of stiffening sheets interposed between said mats and said outside sheets, said mats and said stiffening sheets being corrugated as a unit, and means securing said mats and sheets adjacent opposite edges thereof.

5. As a new article of manufacture, a con-

tainer comprising a pair of mats formed of tissue paper or the like, a pair of outside sheets formed of relatively tough but flexible and expansible paper, and a pair of stiffening paper sheets interposed between said mats and said outside sheets, said mats and said stiffening sheets being corrugated as a unit, and means securing said mats and sheets adjacent opposite edges thereof.

6. As a new article of manufacture, a container comprising a pair of relatively soft mats disposed adjacent each other, a pair of outside sheets formed of relatively tough but flexible material, and a pair of stiffening sheets interposed between said mats and said outside sheets, adhesive means securing said stiffening sheets to said outside sheets, and means securing said mats and sheets adjacent opposite edges thereof.

7. As a new article of manufacture, a container comprising a pair of mats formed of tissue paper or the like, a pair of outside sheets formed of relatively tough but flexible material, and a pair of stiffening sheets interposed between said mats and said outside sheets, said mats and said stiffening sheets being corrugated as a unit, adhesive means securing said stiffening sheets to said outside sheets, and means securing said mats and sheets adjacent opposite edges thereof.

8. As a new article of manufacture, a container comprising a pair of mats formed of tissue paper or the like, a pair of outside sheets formed of relatively tough but flexible paper, and a pair of paper stiffening sheets interposed between said mats and said outside sheets, said mats and said stiffening sheets being corrugated as a unit, adhesive means securing said stiffening sheets to said outside sheets, and means securing said mats and sheets adjacent opposite edges thereof.

FRANK A. BIEDERMAN.
